UNITED STATES PATENT OFFICE.

JULIUS A. BIDWELL, OF IVANPAH, CALIFORNIA.

DESIGN FOR A SCARF-PIN.

SPECIFICATION forming part of Design No. 16,589, dated March 30, 1886.

Application filed February 17, 1886. Serial No. 192,308. Term of patent 14 years.

To all whom it may concern:

Be it known that I, JULIUS A. BIDWELL, a citizen of the United States, residing at Ivanpah, in the county of San Bernardino and State of California, have invented and produced a new and original Design for Scarf-Pins, of which the following is a specification.

My invention consists of a novel design for scarf or other pins, badges, or charms, which will be more fully explained by reference to the accompanying drawings, in which—

Figures 1 and 2 are views of my device.

The feature of my design consists of the representation of a bug or insect having one or more coins arranged upon the convex surface of its back or outer shell, as shown.

Having thus described my invention, what I claim, and desire to secure by Letters Patent, is—

A design for scarf or other pins or badges, consisting of the fac-simile of coins upon the convex surface or back of the bug or insect, substantially as shown and described.

In witness whereof I have hereunto set my hand.

JULIUS A. BIDWELL.
